UNITED STATES PATENT OFFICE.

LYMAN H. COBB, OF FITCHBURG, MASSACHUSETTS, ASSIGNOR TO MARY ELIZABETH JOHNSON, TRUSTEE.

FIREARM.

1,046,268.

Specification of Letters Patent.

Patented Dec. 3, 1912.

Application filed July 3, 1909. Serial No. 505,929.

To all whom it may concern:

Be it known that I, LYMAN H. COBB, a citizen of the United States, residing at Fitchburg, in the county of Worcester and 5 Commonwealth of Massachusetts, have invented a new and useful Improvement in Firearms, of which the following is a specification, accompanied by drawings forming a part of the same, in which—

10 Figure 1 represents a side view of a revolver embodying my present invention, with the sides of the handle removed. Fig. 2 is a side view of the handle and hammer of a revolver, with the sides of the handle 15 removed, showing the hammer in a cocked position. Fig. 3 is a detached view of the hammer spring and adjustable plate to receive the thrust of the spring. Fig. 4 is a detached view of the thrust plate. Fig. 5 is 20 a sectional view of the same on the line 5—5, Fig. 4. Fig. 6 is a central sectional view of the cup shaped washer 10.

Similar characters refer to similar parts in the different figures.

25 My present invention relates to means for employing a spiral spring for the hammer spring of a firearm, with an adjustable abutment plate to receive the pressure of the spring, and it has for its object to provide 30 means for retaining the spring in a compressed position to facilitate its removal from the firearm; and I accomplish this object by means of the construction and arrangement of parts as hereinafter described and pointed out in the annexed claims.

Referring to the accompanying drawings 1 denotes that portion of the framework of a revolver forming the handle.

40 2 is the hammer, and 3 is the hammer spring consisting of a spiral spring carried upon a thrust pin 4 having its end 5 resting in a small recess formed in the rear side of the hammer, and having its opposite 45 end 6 passing through an opening 4^a in an abutment plate 7 held in a fixed position in the frame of a firearm in any suitable manner.

In the present instance the abutment plate 50 7 has its opposite ends adapted to engage notches 8, 8, in the frame of the firearm, by which the abutment plate is held in a fixed position to receive the thrust of the hammer spring 3. One end of the hammer spring 55 3 bears against a shoulder 9 on the thrust

pin 4, and the opposite end is received in a cup shaped washer 10 which bears against the abutment plate 7. The abutment plate 7 is provided with a circular opening 4^a and a short slot 11 communicating with the opening 4^a. The opening 4^a is of the proper size to receive the body portion of the thrust pin 4 and the short slot 11 is of less width than the diameter of the opening 4^a and adapted to receive a neck 12. When the hammer 2 is raised in a cocked position, as shown in Fig. 2, the hammer spring 3 is compressed and the thrust pin 4 is pushed through the opening 4^a in the abutment plate 7. If the end 6 of the thrust pin be 65 then pushed in the direction of the arrow 13, Fig. 2, the neck 12 will be carried into the contracted slot 11 by which the thrust pin will be held from longitudinal movement. By returning the hammer to its normal position as shown in Fig. 1, the thrust pin 4 will be held from following the hammer and the hammer spring 3 will be held in a compressed position allowing the thrust pin 4, the hammer spring 3, and the abutment plate 7, to be removed as a single piece. 75

In order to bring the hammer spring 3 into action, when the parts are again replaced, the end 6 of the thrust pin is pushed in the direction opposite to that shown by 80 the arrow 13, causing the pin 4 to be raised into the circular opening 4^a within which the thrust pin is capable of longitudinal movement.

In order to prevent the thrust pin from 90 being accidentally displaced from the circular opening 4^a the side of the abutment plate 7 next the cup shaped washer 10 is counterbored to form a recess 14, Figs. 4 and 5, said counterbore having a curved 95 bottom to fit the curved surface 15 of the cup shaped washer 10. When the cup shaped washer 10 is inserted in the recess 14 it will be held therein by friction and prevent the displacement of the thrust pin 4 in the abutment plate 7. A pressure upon the end 6 of the thrust pin in the direction of the arrow 13, however, will be sufficient to dislodge the cup shaped washer from the recess 14 when the hammer is cocked, and 100 allow the neck 12 to be pushed into the contracted slot 11.

I claim,

1. A firearm having a hammer pivoted to the frame, a thrust pin with one end engag- 110

ing the rear side of the hammer, a hammer spring arranged to actuate said thrust pin, an abutment plate for said spring removably held in the frame of the firearm, said 5 plate being provided with means for holding said thrust pin from longitudinal movement.

2. A firearm having a hammer pivoted to the frame, a thrust pin with one end engaging the rear side of said hammer, a spiral hammer spring surrounding said pin and arranged to actuate the same, an abutment plate for said spring removably held in the frame of the firearm, and means for 10 detachably connecting said thrust pin and said plate whereby said pin is held from longitudinal movement in either direction.

3. A firearm having a hammer pivoted to the frame, a thrust pin with one end engaging the rear side of said hammer, a spiral hammer spring surrounding said pin and with one end engaging the same, an abutment plate for said spring removably held in the frame of the firearm and having an 15 opening for the passage of said pin, said plate having means for engaging said pin when said hammer is cocked and hold said spring compressed when said hammer is in 20 its normal position.

25 4. In a firearm, a hammer, a thrust pin,

an abutment plate having an opening for the longitudinal movement of said thrust pin and a slot communicating with said opening, a spiral hammer actuating spring inclosing said thrust pin between said abutment plate and a shoulder on said thrust pin, said thrust pin having a neck adapted to enter said slot and hold the pin from longitudinal movement. 35

5. In a firearm, a hammer, a hammer 40 spring, a thrust pin and an abutment plate having an opening for the thrust pin, a slot communicating with said opening, and a recess concentric with said opening.

6. In a firearm, a hammer, a thrust pin, 45 a spiral spring inclosing said thrust pin, an abutment plate having an opening for the longitudinal movement of said thrust pin, a concentric recess, a slot communicating with said opening, said thrust pin having a 50 reduced portion adapted to enter said slot, and a cup shaped washer inclosing the end of the spiral spring and engaging said recess.

Dated this 28th day of June 1909.

LYMAN H. COBB.
